Copy of
Abner J. Blanchard's Design for a Cooking Stove: No. 2.
Inventor of
Patent No. 3,000.
Lancaster May 29, 1855.

Dec. 712

Abner J. Blanchard, of South Reading Mass.

Assignor to

Blanchard, Willmore &c.

Letters Patent No 712. Dated May 29th 1855.

The schedule referred to in these Letters Patent, and making part of the same,

To all Persons to whom these Presents shall come,

Be it known, that I, Abner J. Blanchard, of South Reading, in the County of Essex, and State of Massachusetts, have invented or produced a new ornamental design for a cooking stove; the nature of such design being fully represented by the accompanying drawings, in which Figure 1. denotes a perspective elevation of a cooking stove having the form or configuration constituting such design. Figure 2. is a horizontal section of the side plate, the same being taken through the smallest door. - Figure 3. is a vertical section taken through the center of the larger side door.

In these drawings, A. A. A. are the feet, B. the base-plate - C. D. end and side plates - E. the top plate and cornice, F. is the minor hearth plate, G. the major hearth plate; H. H. I. I. the front doors of the fireplace; K. L. and M. are the side doors.

The ornamental character of each of the members above referred to, is clearly exhibited in the drawings and to an extent sufficient to enable any skillful stove pattern maker to comprehend the same.

What I claim is the design of each of the doors, as well as that of the side plate, the larger hearth plate and the leg.

In testimony whereof, I have hereunto set my signature this twenty eighth day of April A.D. 1855,

witnesses,

Ed
